FIG.2

FIG. 1 of the drawing illustrates a front perspective view of the television receiver of the invention; and FIG. 2 illustrates a rear perspective view of the receiver of FIG. 1.

This is a continuation-in-part of design applications Serial No. D. 73,859 and Serial No. D. 73,858, filed March 7, 1963, and now abandoned.

The dominant features of the design reside in the portions shown in full lines, the design being characterized by the ornamental appearance created by the black-and-opaque-appearing screen covering the viewing area of the television receiver, when the screen is illuminated from the front.
